(57) **CLAIM**

The ornamental design for a container without cap, as shown and described.

DESCRIPTION

FIG. 1 is a three-dimensional perspective view of the container without cap;

FIG. 2 is a front view of the container without cap;

FIG. 3 is a top view of the container without cap;

FIG. 4 is a bottom view of the container without cap;

FIG. 5 is a side view of the container without cap; and,

FIG. 6 is a back view of the container without cap.

The broken lines are shown for illustrative purposes only and form no part of the claimed design.
